UNITED STATES PATENT OFFICE.

JOHN C. HUB, JR., OF CLEVELAND, OHIO.

FASTENER FOR LETTER-FILES.

1,138,872.

Specification of Letters Patent. Patented May 11, 1915.

Application filed December 30, 1909. Serial No. 535,702.

To all whom it may concern:

Be it known that I, JOHN C. HUB, Jr., a citizen of the United States, and a resident of Cleveland, county of Cuyahoga, and State 5 of Ohio, have invented a new and useful Improvement in Fasteners for Letter-Files, of which the following is a specification, the principle of the invention being herein explained and the best mode in which I have 10 contemplated applying that principle, so as to distinguish it from other inventions.

My invention relates in general to paper fasteners, and in particular to fasteners designed to attach a file of papers to any 15 suitable backing. The common forms of fasteners which may be utilized for this purpose, possess the serious fault that a single prong or a single pair of prongs serves both to secure the papers to each 20 other and to the backing; consequently if the prong be opened so that a paper may be removed, it often accidentally happens that the fastener is loosened from all of the 25 papers and the backing, and much time is consumed in rearranging the papers.

My improved device is adapted to entirely 30 obviate this fault, and at the same time it is a device which lends itself to extremely simple and economic methods of manufac- ture.

To the accomplishment of these and related ends said invention, then, consists of the means hereinafter fully described and particularly pointed out in the claim.

The annexed drawing and the following 35 description set forth in detail certain mechanism embodying the invention, such disclosed means constituting, however, but one of various mechanical forms in which the 40 principle of the invention may be used.

In said annexed drawing:—Figure 1 is a perspective view of a cover provided with my device; Fig. 2 is a perspective view of the device, and Fig. 3 is a broken plan of a 45 strip from which the device is manufactured.

The device comprises a sheet metal strip or body 1 of any suitable size. During manufacture of the device a plurality of 50 bodies 1 may be stamped from a single continuous strip, as is illustrated in Fig. 3. During the same operation which stamps the several bodies from a continuous strip, each body is stamped so as to cut therein 55 the two strips or prongs 2 at the ends of the body, and the two strips or prongs 3 in-

termediate of the ends of the body. These prongs, however, remain integral with the body 1 at one end, and it is in this form that they will be offered for sale. When, 60 then, the fastener is to be used, the four prongs are bent upward at right angles to the body and all four prongs are inserted through the backing, the intermediate prongs are then bent down and serve to 65 securely attach the fastener to the backing. Any desired papers may then be attached to the backing by pressing them on the prongs at the end of the body, and then turning such prongs downward.

Fig. 1 illustrates my fastener associated 70 with the ordinary vertical letter file, and it is contemplated that such letter files may be formed with holes adapted to receive the prongs of the fastener so that the complete 75 file will be not only more secure, so far as its fastenings are concerned, but will be neater in appearance.

Supposing my fastener to be secured to a vertical letter file, or other backing, and 80 to have filed thereon a plurality of letters or other papers, if it is desired to withdraw a given paper from the file, the end prongs are first turned upward. The necessary 85 papers may then be withdrawn from the fastener, but during this operation, the fastener is still securely attached to the backing by the intermediate prongs; consequently the papers in the file, which lie 90 below the papers to be withdrawn, will not be disturbed and the fastener cannot be accidentally withdrawn so that such papers 95 will become detached from the file.

It is finally to be noted that any number 100 of fasteners may be stamped from a continuous strip so that they may be manufactured at a trifling cost, and by a simple operation.

Other modes of applying the principle of my invention may be employed instead of 105 the one explained, change being made as regards the mechanism herein disclosed, provided the means stated by the following claim or the equivalent of such stated means be employed.

I therefore particularly point out and distinctly claim as my invention:—

A device of the character described, comprising a substantially rectangular sheet metal body having two long strips stamped 110 therefrom, each of said strips remaining attached to said body at one end and ex-

tending from the points of attachment toward the center of the body, said strips being alined but spaced from each other; and two relatively short strips stamped 5 from said body between the adjacent ends of said long strips, whereby such short strips may be bent up to securely engage the backing of a file and said long strips

may be bent up to engage individual sheets to be filed.

Signed by me this 28th day of December, 1909.

JOHN C. HUB, JR.
